(57) **CLAIM**

The ornamental design for a handle for beach apparatus carrier, as shown and described.

DESCRIPTION

FIG. 1 is a perspective view of the handle for beach apparatus carrier showing my new design;

FIG. 2 is a front elevation view of the handle for beach apparatus carrier of FIG. 1, the rear view appearing the same;

FIG. 3 is a side elevation view of the handle for beach apparatus carrier of FIG. 1, the opposite side being the same;

FIG. 4 is a top plan view of the handle for beach apparatus carrier of FIG. 1; and,

FIG. 5 is a bottom plan view of the handle for beach apparatus carrier of FIG. 1.

The broken lines of FIGS. 1-5 and the area within are environmental only and form no part of the claimed design. The broken line showing of in the views is for illustrative purposes only and forms no part of the claimed design.
